UNITED STATES PATENT OFFICE

ALBERT L. LAMBERT, OF PHILADELPHIA, PENNSYLVANIA, ASSIGNOR TO HEINTZ MANUFACTURING COMPANY, OF PHILADELPHIA, PENNSYLVANIA, A CORPORATION OF PENNSYLVANIA

LATCH FOR AUTOMOBILE DOORS

Application filed October 6, 1925. Serial No. 60,709.

This invention relates to latches for automobile doors, or for other doors in which a wide pane of glass is desired, and to latches which are operable from both sides of the 5 door.

Heretofore in automobile doors it has been customary to have the operating stem of the latch extend straight through the door between the handles on the opposite sides of the 10 door. This construction does not permit the lowering glass panel in the door to extend beyond this stem, and accordingly the width of the glass is limited and restricted.

The principal object of my invention is to 15 provide a latch for doors which permits the glass, whether lowering or fixed, to extend the full width of the door, or nearly so, and at the same time to provide a latch which may be operated from both sides of the door. 20 Another object of my invention is to provide a simple, durable and light latch construction and mounting of the character described. Other objects of my invention will be in part obvious and in part pointed out hereinafter.

25 In accordance with my invention, the operating handle which is at the opposite side of the glass from the latch bar is connected to the latch bar to operate the same by parts which extend across the edge of the glass 30 and door at, or even outside of, the edge of the door, thus permitting the glass in the door to extend between the latch and this operating member to the very edge of the door. If desired, the operating parts which extend 35 across the edge of the door may be enclosed in a housing section which is located and shaped to seat in a recess in the jamb and to engage between two opposite resilient plungers or buffers in the recess, to guide the door into 40 proper position when being closed, and to hold the door, when closed, against vibration and rattling against the jamb.

In order that a clearer understanding of 45 my invention may be had, attention is hereby directed to the accompanying drawings, forming a part of this application, and illustrating one possible embodiment of this invention. Referring to the drawings, Fig. 1 is a cross-sectional view of a lock embodying 50 this invention, shown mounted in a door, and

is taken on the line 1—1 of Fig. 3; Fig. 2 is a similar view, except that it is taken on a different plane, as on line 2—2 of Fig. 3; Fig. 3 is a vertical sectional view thereof, including a fragment of the door jamb, and is taken 55 on the line 3—3 of Fig. 1; and Fig. 4 is a side view of the lock, looking from the outside of the door, the structure being partly broken away. Similar reference characters refer to similar parts throughout the several views 60 of the drawings.

Referring to the drawings, at the outer side of the door 1 is an operating handle 2, which has a shank 3 extending through the outer door panel 4 and through a reinforcing plate 5, positioned against panel 4, and through another plate 6 spaced rearwardly of plate 5. Here this shaft ends. A sleeve 7 is placed on the shank 3 between a flange 8 thereon and the outside of panel 4. Inside 70 the panel, shank 3 is square and engages in a square perforation in the hub 9 of a lever 10, which has an offset portion 11 extending through a slot 12 in plate 6.

At the inside of the door, the operating 75 handle 13 has a square shank 14 extending through the inner door panel 15, through a reinforcing plate 16, positioned against the panel, and through another plate 17, spaced inwardly from plate 16. The shaft extends 80 no further. Inside the panel the square shank 14 of the operating handle engages in a square perforation in the hub 18 of an operating lever 19.

The latch bar 20 is slidably mounted 85 between plates 16 and 17 and is confined between lugs 21 punched in from plate 16, and has a slot 22 penetrated by a pin 23 which is mounted across plates 16 and 17. A spring 24, engaging the rear of the latch bar and secured 90 to lugs 25 on plate 16, constantly urges the latch portion 26 of bar 20 outwardly of the door edge. At its rear end, latch bar 20 has a shoulder 27, against the forward side of which bears one side edge of the lever 19, so 95 that, by turning handle 13 to move lever 19 inwardly, the latch may be retracted. Lever 19 is prevented from overmuch forward movement by engaging pin 23.

30 designates the door edge panel which has 100

its outer edge engaged within the marginal fold 31 of panel 4. A reenforcing strip 32 is secured to the rear of this panel 30, and has an indented longitudinal central portion 33, to which the runway 34 for the window 35 is secured. Where the latch is applied to the door, strip 32 has an angular portion 36 intermediate the window and the outside of the door, and at the inside of the door is cut away and formed with a flange 37 which rests against plate 17. On the outside of the door, plate 5 has a flange 38 secured to strip 32 by screws 39.

Panel 30 is also cut away where the latch 15 is applied to the door, and is formed with a flange 40 which seats against one wall of the angular portion 36 of the reenforcing strip 32.

Plate 16 has a flange 41 extending around the edge of the door to the flange 40 of edge 20 panel 30. Flange 41, however, is formed with an intermediate outwardly projecting portion 42, which is hollow, and preferably tapered vertically, the narrower portion being toward the inside of the door. A recess 43 to receive this door portion 42 is provided in the door jamb 44, and in this recess are located upper and lower resilient plungers or buffers 45, which are engaged and wedged apart when the door wedge 42 enters the jamb recess 43, as when the door is closed. The cooperation of wedge 42 with the recess and plungers serves to locate and guide the door when it is being closed, and keeps the door, when closed, from vibrating and rattling in the jamb.

This door portion 42 also provides a housing for an operating part of the latch mechanism, whereby the latch may be retracted by manipulating the handle 2 on the outside of the door. This portion of the latch mechanism includes a rock shaft 50, which is rotatably housed in the recess formed behind the projecting portion 42. Shaft 50 has a trunnion 51 on one end rotatably seated in a perforation in a strip or plate 52 secured to reenforcing plate 30, and has at its other end a trunnion 53, which is rotatably seated in a perforation in a flange 54 of a plate or strip 55 which is seated within the portion 42 and at its inner end has a flange 56 secured to plate 16. At the inner side of the door, shaft 50 has a lever arm 57, which is connected to operating lever 19 by a link 58. At the outer side of the door, shaft 50 has a lever arm 60, which at its outer end rests on the top of the outer end of operating lever 11. Reenforcing strip 30 has a suitable perforation or aperture 61 through which lever 60 extends. A stop lug 62 is provided on plate 6 to limit downward movement of lever 11. When handle 2 is turned to raise lever 11, the inner end of arm 60 will rise. This will cause shaft 50 to rotate to raise the inner end of arm 57, and by reason of the connection between arm 57 and operating lever 19, this latter lever will

be moved rearwardly and will retract the latch bar 20 and its latch 26. When handle 2 is then released, spring 24 will return the parts to initial position. It will also be noted that when the latch is retracted by turning handle 13, the rock shaft 50 will rotate and its arm 60 will rise, but lever 11 will not rise nor will handle 2 turn. This avoids unnecessary friction and resistance to the operation of the latch from inside the door.

It is to be noted particularly that the glass 35 may extend to the reenforcing strip 32, which is at the very edge of the door. This is possible because the rock shaft 50 is outside thereof, and, in fact, is outside of the door edge itself.

Accordingly it will be seen that the latch construction and mounting permits the window glass, whether lowering or fixed, to be extremely wide, and at the same time provides a latch which may be operated from both sides of the door. The construction is extremely simple, light and durable. The construction also may be arranged to function as a door locating and confining device. Obviously, if desired, the portion 42 need not be extended outwardly of the door edge, and the rock shaft 50 need not necessarily be located outside of the door edge, but may be located to the rear of this edge. Even so, the glass can be wider than would be possible if a latch operating member extended straight across the door between the handles.

As many changes could be made in the above construction and as many apparently widely different embodiments of this invention could be made without departing from the scope thereof, it is intended that all matter contained in the above description or shown in the accompanying drawings shall be interpreted as illustrative and not in a limiting sense.

What I claim is:

1. The combination with a door, of a latch on one side of the door, a handle on the other side of the door for operating the latch, and latch operating mechanism operatively connecting said handle and latch, said mechanism including a rock shaft, a housing projecting outside of the door edge, and said shaft being mounted in said housing outside of the edge of the door, said housing having vertical taper increasing from the inner side of the door, and a door jamb having a recess to receive said projecting housing when the door is closed.

2. The combination with a door, of a latch bar mounted on the door, a first pivoted operating lever, adjacent one side of the door and engaging the bar, a first handle for pivoting said lever to retract the latch bar, a second pivoted operating lever on the opposite side of the door, a second handle for pivoting this lever, a rock shaft extending across the door and offset laterally from said han-

dles, a first arm on said rock shaft engaging over said second operating lever, whereby when said second lever is raised said shaft will be rocked, a second arm on said rock shaft, a link connecting said second arm to said first operating lever, whereby when said shaft is rocked by said second operating lever said latch bar is retracted, said operating levers and rock shaft arms being spaced apart a substantial distance crosswise of the door.

This specification signed this 2 day of October, 1925.

ALBERT L. LAMBERT.
